UNITED STATES PATENT OFFICE

2,468,693

THERMAL RELAY

Josef Stoecklin and Alfred Käch, Baden, Switzerland, assignors to Aktiengesellschaft Brown, Boverie & Cie., Baden, Switzerland, a joint-stock company

Application August 26, 1944, Serial No. 551,405
In Switzerland December 31, 1942

Section 1. Public Law 690, August 8, 1946
Patent expires December 31, 1962

6 Claims. (Cl. 175—294)

1

It is known that electric conductors, machines and apparatus can be protected against overloads by using thermal relays where the tripping element is built into a thermal image of the object which is to be protected. The term "thermal image" designates a device which has the same time-temperature characteristics as the electrical equipment to be protected when the device is heated by the current supplied to, or proportional to the current supplied to, the electrical equipment. This image is generally of the same kind as the protected object itself but reproduced to a smaller scale and in a simplified form.

The prior thermal relays are open to the objections that some types are not readily adjustable for use with electrical equipment of different constructions and sizes, and other types draw considerable power which imposes an undesirable load upon conventional current transformers. Furthermore it is often difficult to obtain a sufficiently large time constant, that is the time until the steady temperature is reached by the known thermal relay with thermal image, and thus attain a sufficiently long interval of time until the tripping temperature is reached.

It must also be noted that the time-temperature curve of electrical machines, apparatus and the like is not a uniform exponential curve, but during the heating resulting from increasing current, the slope of the time-temperature curve of the equipment passes from a higher to a lower value. This condition must also be satisfied by the thermal relay if it is to afford the intended protection in dependence upon the magnitude and previous mode of variation of the power current.

In the thermal relay of this invention, both the thermal tripping member and the heat-storing masses of the thermal image are heated in common by a resistance which is fed by a current proportional to the power current of the equipment to be protected, and the tripping member is combined into a block with the heat-storing masses and the heating resistance; heat insulation of the same or different heat transmission, as may be required, being arranged between the heating resistance and respectively, the tripping member and the heat-storage masses to obtain a displacement of the tripping member in accordance with the temperature of the electrical apparatus to be protected.

In the accompanying drawings:

Fig. 1 is a somewhat schematic view of a thermal relay embodying the invention, the

2

thermal image being shown in longitudinal section; and

Fig. 2 is a transverse section through the thermal relay as taken on line 2—2 of Fig. 1.

A current proportional to the power current of an electrical apparatus which is to be protected, for instance an electrical machine, is developed by a current transformer *a* and flows through a flat strip or ribbon-shaped heating resistance *b*.
 5 10 The resistance strip *b* is a single inverted U-shaped loop in an open-ended duct *c*, and this loop extends around the tripping member *d* which comprises a series of reversely bowed bimetallic plates which absorb a part of the heat developed by the heating resistance. The remainder of the developed heat is absorbed by the metal plate *e*₁ and the end wall of an open-ended metal frame *g* which form the boundary walls of the duct *c*, the heating resistance *b* being spaced from the duct
 15 20 walls by sheets of insulation *f*₁. Sheets of insulation *f*₂ are located between the heating resistance *b* and the tripping member *d*. Interchangeable heat storage plates *e*₂ of different mass are held in contact with the heated wall
 25 30 35 40 45 50 of the frame *g* by a spacer or filler plate *u*, and the block assembly of the heating resistance *b* and heat-absorbing members is encased within the metallic housing *h* which limits the escape of heat to the surrounding atmosphere. The block assembly is supported by bars *j* of low heat conductivity which are secured to a frame or base plate, not shown.

The total mass and the composition of the heat-storage plates *e*₂ are selected in accordance with the time-temperature characteristic of the protected apparatus under various loadings. The inner metallic frame *g* is a fixed part of the thermal relay which, with the metal plate *e*₁, has a constant heat-absorbing and heat-radiating characteristic that may be modified, as desired, by the introduction of heat-absorbing plates *e*₂ of different mass.

The thermal tripping member *d* actuates over the axle *i* and the gear sector *k* a differential gearing *l*, *m*, *n* whose differential wheels *l*, *m* are provided with pointers. The pointer on the free wheel *l* indicates continuously on a scale the temperature of the protected object, whilst the wheel *m* and its pointer can be adjusted by hand to the desired tripping temperature. The thermometer pointer on the wheel *l* can be provided with a maximum indicator pointer not shown in the drawing for the purpose of indicating the maximum temperature reached. The planet wheel *n* causes the tilting lever *o* of switch *p* to turn and

when the tripping temperature is reached this lever passes its dead centre and closes the release contact *p*. If the protected object becomes warm during no-load, for instance a transformer, then this no-load heating can be taken into account on the scale of the thermometer by making the scale of the latter commence only at no-load heating.

The lower support of the tripping member is connected with the bearing of the axle *i* by means of a rigid arm *q*, so that any displacement of the tripping member *d* within the conduit *c* has no effect on the temperature indication and tripping temperature.

The heating current in the resistance *b* can be adjusted by means of the variable shunt *r* to the desired value. It is also expedient to provide the usual compensation for the variable ambient temperature; this has not been shown in the drawing in order not to complicate the figure unnecessarily.

If it is desired to cause instantaneous tripping when large overload currents occur then an electro-magnetic tripping relay *s* is connected in series with the resistance *b*, this relay having two pairs of contacts one of which lies parallel to the tripping contact *p* of the thermal relay, whilst the other pair short-circuits the heating resistance *b* when the electro-magnet *s* is attracted. This limit-current release can of course also occur with a delayed action. The entire relay together with all the accessories is as usual enclosed in a casing *t*. Thermal and limit-release can be indicated by a common signal or by separate signals of the acoustical or optical kind either through a window in the casing *t* or at a remotely located spot.

As can be seen, the thermal image with the thermal relay according to the invention, is not at the same time a mechanical reproduction of the protected object. This possesses the advantage that the same relay can be used for different types of protected objects.

It is expedient to provide the relay with testing terminals which readily enable the relay to be tested in operation at the place of installation without undesirable switching operations.

We claim:

1. A thermal relay for the protection of electrical apparatus of different types and having a preselected time-temperature characteristic, when energized by a current proportional to the current supplied to a particular electrical apparatus, which is substantially identical with the time-temperature characteristic of said particular electrical apparatus; said thermal relay comprising thermal tripping means, heat storage means, heating resistance means in heat-transfer relation to both said thermal tripping means and said heat storage means, layers of heat insulation

material between said heating resistance means and respectively said thermal tripping means and said heat storage means to determine the relative rates of heat transfer thereto, and a metal housing enclosing and spaced from said heating resistance means and cooperating thermal tripping means and heat storage means to limit the radiation of heat therefrom; said heat storage means including a metal body constituting a minimum heat storage mass, and interchangeable metal plates in thermal contact with said metal body to increase the total heat storage mass to a magnitude which develops said predetermined time-temperature characteristic.

15 2. A thermal relay as recited in claim 1, wherein said metal body is an open-ended cylinder.

3. A thermal relay as recited in claim 1, wherein said metal body is an open-ended cylinder of square cross-section, said heating resistance means is adjacent one flat wall of said metal body, and said interchangeable metal plates contact the said flat wall of the metal body.

4. A thermal relay as recited in claim 1, wherein said heating resistance means includes parallel flat strip resistors extending along opposite sides of and separated from said thermal tripping means by certain of said layers of heat insulation material.

5. A thermal relay as recited in claim 4, wherein in said metal body of the heat storage means includes a flat wall parallel to and spaced from one of said flat strip resistors by one of said layers of heat insulation material.

6. A thermal relay as recited in claim 5, in combination with a metal heat-storage plate parallel to and spaced from the other flat strip resistor by a layer of heat insulation material.

JOSEF STOECKLIN,
ALFRED KÄCH.
